UNITED STATES PATENT OFFICE.

JOHN MACDONALD, OF FORT RUSSELL, WYOMING.

URINAL-BASIN WASTE-PIPE.

No. 833,072.

Specification of Letters Patent.

Patented Oct. 9, 1906.

Application filed August 18, 1905. Serial No. 274,720.

To all whom it may concern:

Be it known that I, JOHN MACDONALD, a citizen of the United States, residing at Fort D. A. Russell, in the county of Laramie and State of Wyoming, have invented certain new and useful Improvements in Urinal-Basin Waste-Pipes; and I do hereby declare the following to be a full, clear, and exact description of the invention, such as will enable others skilled in the art to which it appertains to make and use the same.

My invention relates to improvements in urinal-basins; and its object is to provide a simple basin in which the discharge-pipe and vent-pipe are in a vertical line with each other inside the basin, and the former may be easily lifted to allow sediment to flow out.

With this object in view my invention consists in the construction and combination of parts, as hereinafter described and claimed.

In the accompanying drawings, Figure 1 is a vertical cross-section of my improved device, and Fig. 2 is a cross-section of a part thereof.

25 *a* represents the basin or bowl, and *b* the waste-pipe. The bowl is cut away for the reception of the tubular holding-piece having the top flange *c*, which holding-piece is screw-threaded at its lower end, a nut *d* engaging 30 said holding-piece and said waste-pipe, thus securing the latter in place. *e* is a packing between said nut and the bowl.

35 *f* is the discharge-pipe, beveled at *g*, to fit within a correspondingly-shaped recess in the holding-piece. Its lower edge is scalloped, as shown at *h*, to provide passages for the escape of sediment and liquid when the tube is raised. The upper part of the tube *f* is bored out, as shown at *i*, so that it will slide 40 on the tube *m*, which serves as a vent for the gases. *j* is a hood or bell secured to the tube *f* in any desired manner, as by screw-threads and the lock-nut *k*, extending down into the bowl *a* and provided with guiding and strain-45 ing arms *l*.

45 *m* is the vent-tube, removably secured to the tube *f* by a union-joint *n*. The tube *f* is provided with a number of drainage-perforations *p*, located within the bell when the latter is in position.

The ordinary operation will be evident

from the description; but when it is desired to remove sediment the union-joint *n* is loosened and the tube *f*, carrying the bell *j*, is slid upwardly upon the stationary tube *m*, 55 which closes the perforations *p*, thus preserving the gas-seal.

The advantages of the construction shown are that the waste-pipe and vent-pipe are located in a straight line in a vertical plane, so 60 that gases can readily escape and the wastewater flows evenly on all sides of the tube. The trap can be cleaned better and more easily. All foreign matter—as matches, for example—is prevented from flowing down 65 the waste-pipe. The strainer and overflow devices are all combined in one structure. The whole device can be easily lifted to allow sediment to flow out and at the same time a tight gas-seal is provided.

Having thus described my invention, I claim—

1. In a urinal-basin, the combination of a bowl provided with a waste-pipe, a vent-tube supported in line with said waste-pipe and a 75 perforated tube slidably mounted on said vent-tube, said perforated tube having a depending bell attached thereto, substantially as described.

2. In a urinal-basin, the combination of a 80 bowl provided with a vertical waste-pipe, a vertical vent-tube located above and in line with said waste-pipe, and a strainer device provided with perforations located just below said vent-tube, said strainer device being 85 slidably mounted on said waste-pipe, whereby the upward movement of the strainer device will cause the perforations therein to be closed by the vent-tube, thus preserving the gas-seal, substantially as described.

3. In a urinal-basin, the combination of a 90 bowl provided with a waste-pipe, a vent-tube in line with said pipe, and a tube provided with perforations, with a scalloped lower end, and with a strainer device, slidably mounted 95 on said vent-tube, substantially as described.

4. In a urinal-basin, a strainer device, including a tube open at both ends and having its upper part bored out and provided with perforations near its upper end and with 100 scallops at its lower end, a depending bell, provided with arms near its lower edge, and

means for securing said bell to said tube, substantially as described.

5. In a urinal-basin the combination of a bowl provided with a vertically-arranged waste-pipe, a vent-tube located above said waste-pipe and in line therewith, and a strainer device slidably mounted on said waste-pipe and provided with perforations

and a scalloped end and a bell, substantially as described.

In testimony whereof I affix my signature in presence of two witnesses.

JOHN MACDONALD.
